UNITED STATES PATENT OFFICE.

MORGAN JOLLIFFE, OF UNIONTOWN, PENNSYLVANIA.

GRIP FOR COAL-CARS.

SPECIFICATION forming part of Letters Patent No. 636,904, dated November 14, 1899.

Application filed March 1, 1899. Serial No. 707,903. (No model.)

To all whom it may concern:

Be it known that I, MORGAN JOLLIFFE, a citizen of the United States, residing at Uniontown, in the county of Fayette and State of Pennsylvania, have invented a new and useful Grip for Coal-Cars, of which the following is a specification.

The invention relates to improvements in grips for coal-cars.

10 The object of the present invention is to simplify and improve the construction of grips for mining-cars and to increase their durability and efficiency and at the same time enable them to be operated with greater rapidity 15 than heretofore in engaging and releasing a cable.

A further object of the invention is to provide a gripping device of this character which will afford substantially a rigid connection 20 between a cable and a car in the line of draft to enable cars to be hauled both up and down hill and which will be capable of yielding laterally to adapt itself to the position of a car and a cable when passing around a curve and 25 the like.

Another object of the invention is to enable a cable to be firmly gripped and to provide a device which can be quickly adjusted for engaging cables of different diameters.

30 Furthermore, the invention has for its object to provide a device which will enable any of its parts when worn to be readily renewed without discarding the rest of the construction.

35 The invention consists in the construction and novel combination and arrangement of parts hereinafter fully described, illustrated in the accompanying drawings, and pointed out in the claims hereto appended.

40 In the drawings, Figure 1 is a perspective view of a device constructed in accordance with this invention. Fig. 2 is a longitudinal sectional view. Fig. 3 is a transverse sectional view. Fig. 4 is a detail sectional view 45 illustrating the connection between the operating-lever and the gear-wheel, the former being out of engagement with the hub of the latter. Fig. 5 is a detail perspective view of the body portion of the movable jaw, the removable face-plate or section being detached. Fig. 6 is a similar view of the removable face- 50 plate or section of the movable jaw.

Like numerals of reference designate corresponding parts in all the figures of the drawings.

1 designates a frame or body having a removable plate 2 and forming a guide or casing for the shank 3 of a movable jaw 4, which cooperates with a stationary or fixed jaw 5 of the frame or casing. The fixed or stationary 60 jaw 5, which is located at the bottom of the frame or body, extends longitudinally thereof and projects laterally from the same, the said frame or body consisting of a heavy plate, as clearly shown in Figs. 1 and 3 of the accompanying drawings. In order to enable the fixed or stationary plate to be readily renewed should it become worn, it is provided with a removable face-plate or section 6, having a dovetailed lug or shank 7 fitting in a 70 dovetailed recess 8 of the body portion of the jaw, and the removable section or face-plate is secured to the frame or body by a transverse fastening device 9, passing through the parts and consisting of a bolt or rivet.

75 The movable jaw is provided with a corresponding detachable face-plate or section 10, having a dovetailed lug 11 arranged at the inner face of the jaw and terminating short of the outer face thereof and fitting in a corresponding recess 12 of the same, and when the movable jaw is in position the lug 11 will be disposed toward the inner face of the frame or body and will be securely held against accidental displacement.

80 The movable jaw has a concave engaging face extending entirely across it, and the stationary or fixed jaw is provided at its engaging face with a flat outer portion and a narrow rope-receiving groove arranged at its inner portion and forming a central edge or rib located opposite the concave engaging face of the movable jaw. By this construction the device is adapted to engage cables of different diameters, and there is no liability of a 85 cable slipping between the jaws.

85 The removable plate 2, which is bolted or otherwise secured to the body or frame at 15, is provided with rectangular bends to form a rectangular opening for the reception of the 100 shank 3 of the movable jaw, and the said shank is provided with a slot or opening 16, extending longitudinally of it and having recesses 17 in its walls for the reception of a nut

18, which is located near the upper end of the shank and which has its threaded opening disposed centrally of the slot or opening and receiving a screw 19. The nut is detachable, 5 and the screw, which is swiveled to the frame or body, as hereinafter described, is adapted to be rotated to open and close the jaws and to set the same for gripping cables of different diameters. The screw is provided at its 10 upper end with an enlargement or head having a pinion 20 and annularly grooved below the same at 21 to engage a recess or opening 22 of a horizontal flange 23, extending laterally from the top of the frame or body. The 15 threaded engagement of the screw with the nut retains the grooved head in the recess or opening of the top flange of the frame or casting, and when the angularly-bent plate is removed the screw may be readily detached 20 from the flange of the frame or body. The pinion 20, which is beveled, meshes with a vertical bevel gear-wheel 24, journaled on a spindle or stub-shaft 25, which is mounted on a vertical extension 26 of the frame or 25 body. The bevel gear-wheel is provided with an inwardly-extending hub 27, having an annular series of sockets 28, which are adapted to be engaged by a lug or projection 29 of an operating-lever 30, and the latter has a 30 slotted connection with the stub-shaft or spindle to enable the lug to be readily engaged with and disengaged from a socket of the gear-wheel. The inner end of the operating-lever is enlarged, as shown, and the enlarged 35 portion, which is recessed at one side to receive the hub, is provided with a longitudinal slot 31, through which the shaft or spindle passes. When the projection or lug of the lever is disengaged from the hub of the gear-wheel, the latter may be rotated independent 40 of the lever to set the jaws for engaging cables of different diameters. After the jaws have been set to receive a cable the latter will be securely clamped by swinging the lever from one side of the device to the other, 45 and the operator may readily release a car from the cable without leaving his seat by swinging the lever with his foot. The operating-lever by being fulcrumed at one end 50 operates in the nature of a weight or gravity-lock to retain the movable jaw in its engaging position, as the weight of the lever must be lifted in order to release the jaw. The lever is detachably secured to the shaft or spindle by a washer 32 and a split key 33, and the stub-shaft or spindle is detachably mounted on the vertical extension of the body or frame by means of a key or other suitable fastening device. 55

60 The frame or body is provided with longitudinal extensions 34, extending forward and rearward and provided at their inner faces with vertical eyes 35, adapted to receive a reversible coupling device 36, consisting of a bar angularly bent between its ends to arrange the same in different planes. The in-

ner end 37, which is rounded, is arranged in the eye to swivel the coupling device to the frame or body, and it is provided with a shoulder 38 and is threaded at 39 to receive a nut 40, whereby the coupling device is detachably secured to the said eye. The outer end 42, which is located above the inner end, is flattened and bifurcated to receive the draw-bar of a car, and it is provided with a coupling-pin perforation, in which is arranged a coupling-pin 43, preferably connected with the coupling device by a short chain to prevent it from being lost. The coupling device is adapted to be transferred from one end of the 70 device to the other to make the latter either right or left hand, and the swivel connection permits the coupling device and the frame or body to swing laterally on each other to conform to the positions of a car and the cable 75 when the latter is passing around a curve, and the said connection is perfectly in line of the draft, so that cars may be drawn equally well up and down hill. 80

The body is provided at one side with a 90 hook-shaped handle 44, adapted to be arranged at either end of the grip, similar to the coupling device, the latter being mounted on one of the longitudinal extensions and the handle on the other. The handle or grip assists in enabling the operator to engage the device with a cable and disengage it therefrom, and it also provides means for hanging the grip on the upper edge of a car-body when it is not in use. 95

The invention has the following advantages: The grip, which is simple and comparatively inexpensive in construction, is positive and reliable in operation, and while it forms a rigid connection between a car and a cable 100 in the line of the draft to enable cars to be hauled equally as well downhill as uphill it is also capable of a lateral twisting or swivel movement to accommodate itself to the positions of a cable and a car in passing around 105 curves and the like. The jaws are readily adjusted to adapt the device for gripping ropes of different diameters, and the parts when worn or otherwise injured may be readily replaced at a small cost without discarding the rest of the device. The device is quickly operated to connect the car with a cable and uncouple it therefrom, and it may be operated in releasing a car by the foot of a person without necessitating his leaving his 110 position. 115

Changes in the form, proportion, size, and the minor details of construction within the scope of the appended claims may be resorted to without departing from the spirit or sacrificing any of the advantages of this invention. 120

What is claimed is—

1. A device of the class described comprising a frame or body having a fixed jaw, a movable jaw, means for operating the same, and a coupling device provided with means for engaging the draw-bar of a car and having a 130

swivel connection with the frame or body, said swivel connection being rigid in the line of the draft and permitting the coupling device and the frame or body to move laterally on each other, substantially as and for the purpose described.

2. A device of the class described comprising a frame or body, fixed and movable jaws, means for operating the same, and a coupling device having a swivel connection with the frame or body and arranged to turn laterally thereon, said coupling device being provided with means for engaging the draw-head of a car substantially as described.

15 3. A device of the class described comprising a frame or body having a fixed jaw, a movable jaw mounted on the frame or body, means for operating the same, and a coupling device having one end bifurcated to receive the draw-bar of a car, and having its other end swiveled to the frame or body, substantially as described.

4. A device of the class described comprising a frame or body having a fixed jaw and provided at its ends with eyes, a movable jaw mounted on the frame or body, means for operating the movable jaw, and a coupling device detachably swiveled in one of the eyes, and adapted to be transferred to the other eye, substantially as described.

5. A device of the class described comprising a frame or body having a fixed jaw, a movable jaw mounted on the frame or body, means for operating the movable jaw, and a reversible coupling device provided at its outer end with a coupling-pin to engage the draw-bar of a car and swiveled to the frame or body and adapted to be arranged at either end thereof, substantially as described.

40 6. A device of the class described comprising a frame or body having a fixed jaw, a movable jaw mounted on the frame or body, means for operating the movable jaw, and a coupling device having a straight portion adapted to be coupled to the draw-bar of a car, and a handle forming a grip and being hook-shaped, whereby the device is adapted to be hung on the body of a car, substantially as and for the purpose described.

50 7. A device of the class described comprising a frame or body having a fixed jaw, a movable jaw, a screw mounted on the frame or body and adapted to actuate the movable jaw, an operating-lever, and gearing connecting the operating-lever with the screw, said operating-lever being adapted to carry the movable jaw into and out of engagement with the cable, and capable of holding such jaw in its engaging position, substantially as described.

60 8. A device of the class described comprising a frame or body having a fixed jaw, a movable jaw, a screw mounted on the frame or body and engaging the movable jaw, a lever, and gearing connecting the lever with the screw, said lever being arranged to be disengaged from the gearing to permit the screw to be operated independently of it to set the

device for cables of different diameters, substantially as described.

9. A device of the class described comprising a frame or body having a fixed jaw, a movable jaw having a slotted shank, a nut detachably interlocked with the shank at the slot thereof, a screw engaging the nut, and means for operating the screw, substantially as described.

70 10. A device of the class described comprising a frame or body having a fixed jaw, a movable jaw having a slotted shank and provided in the walls of the slot with recesses, a nut detachably arranged in the recesses, a screw engaging the nut and detachably swiveled to the frame or body, and means for operating the screw, substantially as described.

80 11. A device of the class described comprising a frame or body having a fixed jaw, a movable jaw mounted on the frame or body and having a shank, a nut detachably mounted on the shank, a flange extending from the frame or body and having a recess or opening, a screw engaging the nut and having a grooved head interlocked with the said flange, and provided with a pinion, and a gear meshing with the pinion, substantially as described.

90 12. A device of the class described comprising a frame or body having a fixed jaw, a movable jaw mounted on the frame or body, a screw engaging the movable jaw and having a pinion, a gear meshing with the pinion, and a lever detachably interlocked with the gear, adapted to rotate the same, and capable of releasing the gear to permit an independent rotation of the screw, substantially as described.

100 13. A device of the class described comprising a frame or body having a fixed jaw, a movable jaw, a screw engaging the movable jaw and carrying a pinion, a gear meshing with the pinion and having a hub provided with sockets, and a lever having a slotted connection with the device and provided with a lug or projection adapted to engage the sockets of the hub, substantially as described.

110 14. A device of the class described comprising a frame or body portion provided with a fixed or stationary jaw having a dovetailed recess 8, a removable face-plate having a dovetailed lug fitting in the said recess, a fastening device passing through the lug and securing the face-plate to the stationary or fixed jaw, a movable jaw provided with a dovetailed recess 12 extending from its inner face and terminating short of its outer face, and a removable face-plate 10 provided at its inner edge with a dovetailed lug fitting in the recess 12 of the movable jaw and retained therein by the frame or body, substantially as described.

120 15. A device of the class described comprising a frame or body, and the fixed and movable jaws, one of the jaws being provided with a continuous concave face extending entirely across it, and the other jaw being provided with an inner narrow groove and hav-

ing an outer flat face, whereby the device is adapted to grip a cable of any diameter, substantially as described.

16. A device of the class described comprising a frame or body, fixed and movable jaws, means for operating the same, and a coupling device consisting of a longitudinally-disposed bar swiveled at its inner end to the frame or body and having its outer end bifurcated to receive the draw-bar of a car and perforated for the reception of the coupling-pin, substantially as described.

17. A device of the class described comprising a frame or body, a coupling device for

connecting the same to a car, a fixed jaw, a movable jaw, a screw mounted on the frame or body for operating the movable jaw, a pinion mounted on the screw, a gear meshing with the pinion, and means for operating the gear, substantially as described.

In testimony that I claim the foregoing as my own I have hereto affixed my signature in the presence of two witnesses.
